UNITED STATES PATENT OFFICE.

WILLIAM EBBITT, OF NEW YORK, N. Y.

IMPROVEMENT IN STEAM-NOZZLES.

Specification forming part of Letters Patent No. 140,902, dated July 15, 1873; application filed April 30, 1873.

To all whom it may concern:

Be it known that I, WILLIAM EBBITT, of the city, county, and State of New York, have invented a new and Improved Steam-Nozzle; and I do hereby declare the following to be a full, clear, and exact description thereof, which will enable those skilled in the art to make and use the same, reference being had to the accompanying drawing forming part of this specification, which drawing represents a longitudinal central section of my invention.

This invention relates to a steam-nozzle which is provided with a conical spout that is situated in line with the exhaust-pipe and fits into the mouth-piece of the nozzle, leaving between its outer surface and the inner surface of said mouth-piece an annular space that communicates with the steam supply-pipe in such a manner that steam admitted through said supply-pipe rushes out through the annular space between the spout and mouth-piece, and by the current of steam thus created the air in the spout and in the exhaust-pipe is rarefied. The conical spout is secured in position by means of a screw-thread, or other equivalent means, so that it can be moved in or out, and that the annular space between said spout and the mouth-piece can be regulated, the mouth-piece being fitted into a socket formed in a flange on the body of the nozzle, so that access can be had to the conical spout, and the annular space between the spout and the mouth-piece can be adjusted without disturbing the connecting-pipes.

In the drawing, the letter G designates my steam-nozzle, which connects by a pipe, H, with the steam-boiler, and by a pipe, I, with the space from which the air is to be exhausted. The steam-pipe H leads into a chamber, n, from the center of which rises a conical spout, J, that is situated in line with the exhaust-pipe I and extends up into the

mouth-piece K of my nozzle. Said mouth-piece is also tapering, and the steam admitted through the pipe H rushes out through the annular space o between the spout J and the mouth-piece K, and as it passes out of this annular space it carries with it a portion of the air contained in the spout J, and thereby the air in the exhaust-pipe I is rarefied. A check-valve, p, which is situated between the spout J and the exhaust-pipe I prevents the steam from passing into said exhaust-pipe, and when the air in the spout is rarefied by the current of steam, this valve opens, and the air in the exhaust-pipe is allowed to rush out. The spout J is secured in the chamber n by means of a screw-thread, or any other equivalent means, so that it can be adjusted up or down, and that the annular space o can be increased or diminished, according to the pressure of steam injected through the pipe H. On the body of the nozzle G is formed a flange, p', forming a socket for the reception of the bottom flange of the mouth-piece K, which is secured in position by screws g. By this arrangement I am enabled to get access to the spout J whenever it may be desired without being obliged to disconnect the pipes H or I, and I can adjust the spout J with ease and facility.

What I claim as new, and desire to secure by Letters Patent, is—

The body of the nozzle G, formed with a flange, p', in combination with the mouth-piece K and adjustable spout J, all constructed and arranged to operate as shown and described.

This specification signed by me this 26th day of April, 1873.

WM. EBBITT.
